GARBAGE CAN RACK

William H. Harrell, P.O. Box 8393,
Nashville, Tenn. 37207

Filed June 1, 1972, Ser. No. 258,912

Term of patent 14 years

Int. Cl. D7—99

U.S. Cl. D7—189

FIG. 1 is a top perspective view of a garbage can rack, showing my new design;

FIG. 2 is a top plan view;

FIG. 3 is a side elevational view; and

FIG. 4 is an end elevational view.

I claim:

The ornamental design for a garbage can rack, as shown and described.
